UNITED STATES PATENT OFFICE.

ANSON G. BETTS, OF TROY, NEW YORK.

LEAD-REFINING APPARATUS.

No. 827,702.

Specification of Letters Patent.

Patented Aug. 7, 1906.

Application filed October 31, 1902. Serial No. 129,548.

To all whom it may concern:

Be it known that I, ANSON G. BETTS, a citizen of the United States, residing at Troy, county of Rensselaer, and State of New York, have invented certain new and useful Improvements in Lead-Refining Apparatus, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification, similar characters referring to similar parts in the several figures therein.

Figure 1 of the drawings is a view in side elevation of an electrolytic vat, partly broken away, showing several of the electrodes. Fig. 2 is a vertical cross-section of the same, taken on the broken line 2 2 in Fig. 1, the electrodes being shown in elevation. Fig. 3 is a similar view showing an electrode in section. Fig. 4 is a cross-section taken on the broken line 4 4 in Fig. 3 through the lug of the electrode and the support therefor. Figs. 3 and 4 are drawn on a larger scale than the other figures.

My invention relates to electrolytic apparatus, and particularly to apparatus adapted for electrolytic refining of lead, as in pursuing the method set forth in United States Letters Patent No. 679,824, granted to me August 6, 1901, to which patent reference may be had for a more complete understanding of the present invention.

Certain objects of the present invention are to provide a means effective under various circumstances for connecting the electrodes with the source of electric energy, to facilitate the manufacture of certain of the electrodes, and to properly support the electrodes in the electrolytic vat.

Referring to the drawings, 1 represents an electrolytic vat which may be of any known form adapted to contain the electrolyte 2 and the cathodes 3 and anodes 4. These electrodes 3 and 4 may be supported in the vat in any known manner, preferably by providing them with oppositely-projecting lugs 5, adapted to rest upon the top edges of the vat or suitable supports erected therefrom, the lugs on the cathodes being adapted to overhang the bus-bar 6, extending along one side of the vat, and the lugs on the

anodes being adapted to overhang the bus-bar 7, extending along the other side of the vat, said bus-bars being connected with the respective poles of a suitable source of electric energy (not shown) in any known manner.

The anodes comprise plates of unrefined cast-lead. The cathodes comprise, preferably, thin plates of iron coated with lead, substantially as set forth in said Patent No. 679,824.

The several electrodes are preferably provided with terminals of copper secured thereto as a means for connecting said electrodes with the respective bus-bars. To facilitate the establishment and maintenance of such connection, I provide each of the several bus-bars, which are preferably formed of copper, with a relatively wide trough or channel 8, having formed in the bottom thereof a series of wells 9 of relatively small cross-sectional area containing a fluid metal, as mercury 10, adapted to receive the respective copper terminals on the electrodes, which are preferably in the form of pins 80 adapted to freely enter the respective wells and be immersed in the fluid metal contained therein. The copper terminal pins may be connected with the electrodes in any known manner. I have shown a copper terminal 85 pin 11, provided with a flattened shank 12, riveted to the overhanging portion of a lug 5 on the cathode in Fig. 2 of the drawings.

As a preferred means for providing the anodes with copper terminals I provide the 90 overhanging lug of the anode with a socket 17 and provide the terminal pin 13 with a tapered end 14, which is driven into said socket. This manner of connecting the terminal pins with the anodes is simple and effective and permits the easy removal of the terminal pin from the anode when the body of the anode has been decomposed by electrolysis.

The terminal pins being immersed in the 100 fluid metal, a perfect connection is insured at all times under various circumstances which would tend to render more or less ineffective other forms of connection. It will be readily seen that slight inaccuracy in locating the 105 terminal pins, as well as slight disarrangement of the electrodes, will not impair the connection formed in the above-described manner. The end of the terminal pin being immersed in the mercury is protected from 110

atmospheric action and soon becomes amalgamated, thereby insuring effective conductive action.

The anodes being plates of cast-lead have 5 certain edge surfaces inclined relatively to the plane of the plate, due to the draft of the pattern used in forming the mold in which the plates are cast. Thus the under surface 15 of the anode-lug 5 is inclined relatively to the plane of the plate, so that if said surface be permitted to rest upon a horizontal surface, as the upper edge of the vat, the anode will hang in an inclined instead of vertical position in the vat.

15 To insure the proper pendent position for the anode, I prefer to provide the vat with an upwardly-presented knife-edge support 16, adapted to engage said inclined surface 15 on the anode-lug at about the middle thereof, as 20 shown in Fig. 4, whereby the anode is supported in a vertical plane within the vat.

By providing the bus-bar with a trough, in the bottom of which the wells for the fluid metal are formed, provision is made for the 25 overflow of the fluid metal from the wells, due to a too deep immersion therein of the terminal pins, the overflow of fluid metal being thus retained and permitted to flow back into the wells when the pins are less deeply 30 immersed therein. The relatively great width of the trough permits any of the fluid metal forced out of the wells to spread with but little increase in depth, so that a considerable variation is permitted in the depth 35 to which the terminal pins are immersed in their respective wells without varying greatly the area of contact between the terminal pin and fluid metal, which would cause material variation in the resistance to the passage of 40 the electric current. By the use of the relatively wide trough with wells of small cross-sectional area I can secure all the advantages of a receptacle for the fluid metal of the length and width of the trough and depth of the 45 wells with a minimum supply of fluid metal.

What I claim as new, and desire to secure by Letters Patent, is—

1. In an electrolytic apparatus, the combination with an electrolytic vat; a bus-bar 50 provided with a relatively wide trough-shaped cavity and a plurality of wells of relatively small cross-sectional area opening in the bottom of said cavity; and fluid metal in said wells; of a plurality of electrodes sup-

ported within said vat; and connections between said bus-bar and the respective electrodes having terminals immersed in the fluid metal in the respective wells, substantially as described. 55

2. In an electrolytic apparatus, the combination with an electrolytic vat; a bus-bar provided with a relatively wide trough-shaped cavity and a plurality of wells of relatively small cross-sectional area opening in the bottom of said cavity; and fluid 60 metal in said wells; of a plurality of electrodes supported within said vat, and severally having a lug overhanging said bus-bar; and terminals depending from the overhanging lugs on said electrodes and immersed in 65 the fluid metal in the respective wells, substantially as described. 70

3. An electrical connection comprising in combination a bus-bar provided with a relatively wide trough and a plurality of wells of 75 relatively small cross-sectional area formed in the bottom of the trough; fluid metal in said wells; and a plurality of conductive members having terminals immersed in the fluid metal in the respective wells, substantially 80 as described.

4. In an electrolytic apparatus, the combination with a bus-bar provided with a relatively wide trough and a plurality of wells of 85 relatively small cross-sectional area formed in the bottom of said trough; and fluid metal in said wells; of a plurality of electrodes of unrefined cast-lead severally provided with 90 sockets; means for supporting said electrodes; and terminal pins driven into the respective sockets and immersed in the fluid metal in the respective wells, substantially as described. 90

5. In an electrolytic apparatus, the combination with an electrode comprising a plate 95 of cast metal having a lug formed with an under surface inclined to the plane of the plate; of an electrolytic vat having an upwardly-presented knife-edge adapted to receive said inclined surface of the lug of the electrode, 100 substantially as described.

In testimony whereof I have hereunto set my hand this 27th day of October, 1902.

ANSON G. BETTS.
